UNITED STATES PATENT OFFICE

HUGH W. BATCHELLER, OF WORCESTER, MASSACHUSETTS

ELECTRIC SWITCH

Application filed April 9, 1929. Serial No. 353,779.

The chief object of this invention is to provide a simple and durable electric switch which includes a movable circuit closer of such form and construction that it is free from liability to be fused or otherwise injured or disabled in performing its function, and actuated by a hand piece or carrier which is movable to close and break the circuit in which the switch is included, either by rotation or rectilinear movement of the hand piece.

Other objects will appear hereinafter.

Of the accompanying drawing forming a part of this specification,—

Figure 1 is a sectional view of a switch embodying one form of the invention, the circuit closer being shown in its circuit-closing position.

Figure 2 is a section on line 2—2 of Figure 1.

Figure 3 is a view similar to Figure 2, showing the circuit closer in its circuit-breaking position.

Figure 4 shows in perspective the conductors shown by Figures 1, 2 and 3, and their gap-separated terminals.

Figure 5 is a perspective view of the hand piece or carrier shown by Figure 1.

Figure 6 is a section on line 6—6 of Figure 5.

Figure 7 is a view similar to Figure 6, showing a modification.

Figure 8 is a side view of a switch embodying another and the preferred form of the invention.

Figures 9 and 10 are sectional views of the body and carrier shown by Figure 8, the conductors being omitted.

Figure 11 is a fragmentary view similar to a portion of Figure 9, showing the conductors.

Figure 12 is a fragmentary rear view looking toward the inner side of the portion shown by Figure 11.

The same reference characters indicate the same parts in all of the figures.

The switch shown by Figures 1 to 6 inclusive, comprises an insulating body 12, preferably composed of bakelite. Fixed in said body and insulated from each other

thereby, are two spaced apart conductors 13, each extending through the body and provided at the inner side thereof with gap-separated terminals 14, formed to contact simultaneously with the movable circuit closer hereinafter described, the terminals being bent at right angles with the conductors and bearing on the inner side of the body 12. Each terminal is provided with a recess 15 (Figures 2 and 3) for a purpose 60 hereinafter described.

An insulating carrier, composed of a cylindrical body portion or hand piece 16 having a flange 17, is movably connected with the body 12 by a frame which includes a central portion having an orifice 18 constituting a bearing in which the hand piece is rotatable, oppositely projecting ears 19, adapted to be attached to a structure supporting the switch, and hooked ears 20 engaged with the outer side of the body 12, as shown by Figure 1, said ears confining the body 12 and hand piece flange 17 spaced apart, the terminals 14 being between the body and the flange.

Circuit closing means, preferably composed of two metallic conducting members, which may be either balls 21, or slugs 21a (Figure 7), is movable by the rotation of the hand piece 16 to either of the two predetermined positions shown by Figures 2 and 3. When said members are in Figure 2 position, they contact simultaneously with the terminals 14 and bridge the gap to close the circuit, and when they are in Figure 3 position, the gap is not bridged and the circuit is broken, the members 21 entering the recesses 15.

The circuit closing members are guided and positively controlled by the hand piece and are pressed yieldingly by springs 23, toward the terminals 14, the springs and portions of said members being contained in longitudinal sockets 24 in the hand piece. The springs act through the members 21 to press the carrier flange 17 against the frame center.

Figures 8 to 12, inclusive, show a simplified and more compact construction, eliminating the frame above described. In said figures, the body designated by 25, has a flat back and is attachable, as by screws 26, formed in the

5 marginal portion of the body, to a support 27. The central portion of the body is thickened and provided with a circular orifice 28, constituting a bearing for the hand piece or carrier 29, which includes a cylindrical inner portion rotatable in said bearing, and an end portion 30.

10 The conductors, here designated by 31, are inserted in a recess 32 (Figure 9) formed in the flat back of the body, their outer sides being flush with said back. The body is provided with metallic bushings 33, whose outer ends project into the recess 32, and enter holes formed for their reception in the conductors 31. Said ends are reduced in thickness to enable them to be upset on the conductors and thereby secure the latter to the body, as shown by Figure 11. The bushings are tapped to engage binding screws 34, which secure conducting wires 35 to the conductors 31.

15 The body is provided with a stop shoulder 36 (Figure 9) which cooperates with a complementary stop shoulder 37 on the hand piece 29, in limiting outward movement of the hand piece in the bearing 28. The conductors are provided with terminals 38, formed like the terminals 14 above described, and separated from each other by a gap coinciding with the axis of the hand piece 29.

20 30 The circuit closer includes two members 39, backed by springs 40, said members and the conductor terminals 38 functioning like the members 21 and terminals 14 above described.

25 The switch last described has several advantages over that shown by Figures 1 to 7, including simplicity and compactness, and the ease and convenience with which its parts may be assembled. The body 25 may be molded in a variety of ornamental forms, 40 with the bushings 33 embedded in it, and the recess 32 formed in its back. The hand piece 29 is insertable in the bearing from the back of the body, its insertion being limited by the stops 36 and 37. After the insertion of the hand piece in the body, the springs 40 and members 39 may be dropped into the carrier sockets, and the conductors 31 may be secured to the body, the assembly being thus completed, the terminals of the conductors preventing escape of the members 39 from the sockets. The stop member 37 of the hand piece is confined against the stop member 36 of the body by the conjoint action of the springs and the members 39, the springs pressing said members against the conductor terminals.

30 It will be seen that in each of the described embodiments of the invention, the switch is provided with a bearing in which the hand piece is rotatable on an axis coinciding with the gap separating the conductor terminals, and that the circuit closing members are eccentric to said axis and movable from one predetermined position to the other by a partial rotation of the hand piece, the bearing

in the preferred embodiment of the invention being formed in the insulating body, and in the other embodiment in the holding frame.

70 It is obvious that the circuit closer may be provided with a single gap closing member eccentrically located at one side of the axis of the carrier, instead of by two members eccentrically located at opposite sides of said axis, two members being preferable.

75 In each of the described embodiments of the invention, the circuit closer includes a hand piece designated by 16 in Figures 1 to 7, and by 29-30 in Figures 8 and 10.

80 Said hand piece projects outward from the body at an invariable angle therewith, there being no swinging or pivotal connection between the hand piece and the body, so that the structure does not include the element of weakness involved by such swinging or pivotal connection.

85 The hand piece and the gap bridging or circuit closing means carried thereby constitute a compact element of the switch, adapted to be conveniently assembled with the other elements, and free, as above stated, from pivotal or swinging connections therewith, so that the switch as a whole is of strong, simple and durable construction.

90 I claim:

95 1. An electric switch comprising an insulating body adapted to be fixed to a support and provided with a bearing constituting a guiding means whereby a movable hand piece may be rotatably guided in opposite directions in a predetermined path relative to said body, spaced apart conductors fixed to the body and insulated from each other thereby, said conductors having gap-separated terminals formed to contact simultaneously with circuit closing means, a circuit closer including an insulating rotatable hand piece projecting outward from said body and adapted to turn in opposite directions in said bearing and guided in a predetermined path thereby, and spring pressed circuit closing means movable in and guided by the hand piece and yieldingly projected from the inner end thereof, to yieldingly enter and bridge said gap when the hand piece is turned in one direction, and retreat from the gap when the hand piece is turned in the opposite direction, the hand piece being maintained at an invariable angle with the body by said bearing.

100 2. An electric switch as specified by claim 1, the circuit closing means being embodied in two members movable in the rotatable hand piece at opposite sides of the axis thereof, and springs yieldingly projecting said members from the inner end of the hand piece.

105 3. An electric switch as specified by claim 1, the circuit closing means being embodied in two members movable in the rotatable hand piece at opposite sides of the axis thereof, and springs yieldingly projecting said mem-

bers from the inner end of the hand piece, the carrier being insertible in said bearing from the inner end of the body, the hand piece and body being provided with complementary
5 stop members maintained in contact with each other by said springs.

In testimony whereof I have affixed my signature.

HUGH W. BATCHELLER.
